(57) **CLAIM**

The ornamental design for a transfer robot, as shown and described.

DESCRIPTION

The patent or application file contains at least one drawing executed in color. Copies of this patent or patent application publication with color drawing(s) will be provided by the Office upon request and payment of the necessary fee.

1. Transfer robot

2. Transfer robot

1.1 : Front

1.2 : Back

1.3 : Left

1.4 : Right

1.5 : Top

1.6 : First perspective view

1.7 : Second perspective view

2.1 : Front

2.2 : Back

2.3 : Left

2.4 : Right

2.5 : Top

2.6 : First perspective view

2.7 : Second perspective view

The transfer robot is used for transporting materials and goods; Bottom views of designs 1 and 2 are omitted since they are not easy to see or cannot be seen during usage.

1 Claim, 14 Drawing Sheets
